Patented Oct. 23, 1917.

2 SHEETS—SHEET 2.

UNITED STATES PATENT OFFICE.

ALBERT S. HOWELL, OF CHICAGO, ILLINOIS, ASSIGNOR TO BELL & HOWELL COMPANY, OF CHICAGO, ILLINOIS, A CORPORATION OF ILLINOIS.

WINDING AND REELING MECHANISM FOR MOTION-PICTURE APPARATUS.

1,243,739.

Specification of Letters Patent.

Patented Oct. 23, 1917.

Original application filed April 22, 1915, Serial No. 23,020. Divided and this application filed September 27, 1915. Serial No. 52,832.

To all whom it may concern:

Be it known that I, ALBERT S. HOWELL, a citizen of the United States, and a resident of the city of Chicago, county of Cook, and 5 State of Illinois, have invented certain new and useful Improvements in Winding and Reeling Mechanism for Motion-Picture Apparatus, of which the following is a specification.

10 My invention relates to the art of cinematography and, more particularly, to the feeding and reeling of the strip or strips of film employed in the motion picture machines of divers types. While my invention 15 is more particularly adapted to a machine for printing the positive film from the negative film, it is also capable of being employed in connection with a projecting apparatus for the purpose of rewinding the film, either 20 simultaneously with the projecting of another film, or after said film has been fed through the machine and it is desired to rewind it during the stoppage of the projecting mechanism of the apparatus.

25 It is an object of my invention to provide a winding and reeling mechanism that is simple in its operation so that it may be manipulated by an unskilled mechanic or novice. Another object of my invention is 30 the provision of means for reeling a film, whether the same be a negative or a positive film, either after projection in a display apparatus or after being printed in a printing machine. Still further objects of my invention 35 are the provision of a reeling mechanism that is capable of being employed upon or adapted to cinematographic machinery already installed and in use; and to provide a reeling mechanism that is not complicated 40 in its operation and comparatively inexpensive to manufacture.

I prefer to accomplish the objects of my invention by the means and in the manner hereinafter fully described and as more particularly pointed out in the claims, reference being had to the accompanying drawings forming a part of this specification, wherein,

Figure 1 is a vertical side elevation of a motion picture apparatus, commonly known 50 as a "printing machine," showing my invention embodied therein.

Fig. 2 is a transverse axial section taken on line 2-2 of Fig. 1, of a fragmentary

portion of the apparatus and drawn to an enlarged scale.

Fig. 3 is an enlarged detail of the belt-tightener showing the same in its two extreme positions.

For the purpose of simplifying the illustrating and describing of my invention, I 60 have shown the same as applied to a printing machine such as is disclosed in an application for Letters Patent of the United States filed by me April 22, 1915, Serial No. 23,020, whereof my present application is a 65 division.

In the drawings, similar reference characters are employed to indicate the same parts throughout the various views.

Referring to said drawings, it will be observed the numeral 10 designates a suitable base that is provided with a vertically disposed standard 11 adapted to support the operating mechanism of a motion picture printing apparatus. Standard 11 is pref- 75 erably hollow and of substantially rectangular cross-section for the purposes herein-after described. A cylindrical lamp house 12 is mounted upon the rear wall of said standard and provides a suitable mount for 80 an electric motor 13 whereby the mechanism is adapted to be actuated.

Mounted upon one of the side walls of the standard 11 is an irregularly-shaped plate 14 (Fig. 2) on which are secured divers parts of the mechanism and through which the main drive-shaft 15, which is journaled in said standard, extends. The outer end of the shaft 15 adjacent this plate is provided with a pulley 16 which is driven by a belt 17 connecting the same with the pulley 18 on the shaft of the motor 13. Between the pulley 16 and the bearings of shaft 15 and back of plate 14 the shaft is provided with a gear 19 that meshes with a larger gear 20, the shaft 21 of which latter is above and has its axis in substantially vertical alinement with the axis of shaft 15. Gear 20 meshes with two smaller gears 22 and 23, the shafts 24 and 25 whereof are 90 likewise journaled in the standard 11 and extend through the plate 14 in horizontal planes above and below the horizontal plane of the axis of shaft 21.

A substantially horizontally disposed angular arm 26 is secured to and projects for-

wardly from the front wall of the base 10 and has a bearing in its outer end for a transverse stub-shaft 27 that is provided with a take-up spool 28 for the positive film upon one of its extended ends and has a grooved drive pulley 29 upon its opposite end. Intermediate its ends said arm 26 is provided with a bearing for another transverse stub-shaft 30, one extended end 10 whereof carries a take-up spool 30^a for the negative film and has a grooved drive pulley 31 which is mounted upon its opposite extended end. A belt 32 passes around pulleys 29 and 31 and connects and drives said 15 pulleys from a smaller grooved pulley 33 carried by the outer end of shaft 24, hereinbefore mentioned.

At or adjacent its upper end the standard 11 is provided with a substantially V-shaped 20 supporting bracket 34 securely bolted thereto and to the ends of the arms of which a suitable elongated or oval-shaped plate 35 is secured. Bearing bosses are provided in the ends of each of the respective arms of 25 bracket 34 through which are disposed stub-shafts 36 and 37. The latter shaft 37 is preferably non-rotatable and is adapted to afford an arbor for a spool of sensitized positive film 38, while the former stub-shaft 30 (36) is preferably rotatable and is adapted to carry a spool 39 of a roll of negative film 40 that rotates therewith. Rotatable stub-shaft 36 extends laterally beyond its bearings opposite the spool 39 where it is provided with a fixed grooved pulley 41 driven by a belt 42 connecting the same with a pulley 43 fast on the main shaft 15, adjacent pulley 16. Belt 42 does not travel direct to the pulley 41 but in the path thereof are 40 interposed idlers 44 and 45, the former of which rotates loosely upon the adjacent extended end of the shaft 21 and the latter idler (45) is journaled on a spindle 46 upon the movable arm 47 of a suitable bell crank 45 or belt tightener 48. This belt tightener is loosely pivoted upon the end of shaft 21 and has an elongated arm 48 in the end of which is a stub 49 to engage suitable recesses or sockets 50 in the ends of a segmental-shaped stop-plate 51. Under ordinary conditions, in other words, when the apparatus is being operated as a printing machine, this arm 48 is in its uppermost position so that the belt 42 is loose and therefore does 55 not drive the pulley 41 on which the negative film is reeled, but when it is desired to rewind the negative film from its lower spool after the printing operation has been completed, the arm 47 is moved to its lowermost position to tighten the belt 42 and after the film has been unthreaded from the usual feeding sprocket and other elements adjacent the aperture element, the same is passed over a small idle roller 52, 60 mounted adjacent the lower edge portion

of plate 35, and secured to the upper spool 39 upon which it will be rewound. This rewinding mechanism may be readily and conveniently employed to rewind either the negative film from spool 39 or the positive 70 film from its spool 38, as all that it is necessary to do is to unthread the film from the feeding sprockets, etc., and thread it directly over the roller 52 from its respective lower spool to the rewind spool 39, it, of 75 course, being understood that all of the mechanism for moving the film past the aperture element is first thrown out of operation by a suitable clutch mechanism upon the main-shaft 15.

This clutch mechanism preferably comprises a structure such as illustrated in Fig. 2 of the drawings and as fully set forth in an application for Letters Patent of the United States, filed by me February 13, 1915, Serial Number 7,932; for stop and recoil mechanism for motion picture apparatus.

By reference to Fig. 2 of the drawings, it will be seen that shaft 15 is extended a considerable distance beyond its bearings and is provided with a reduced portion that forms a shoulder 53 and has a splineway 54 in said reduced portion for the purpose of securing one of the members of a friction clutch thereto. This clutch member preferably comprises a hollow sleeve 55 that surrounds the outer reduced end of shaft 15 and is splined thereto by a key 56 fitting into the splineway above mentioned and is locked to the interior groove of the sleeve by a pin 57. The inner end of the sleeve, facing the standard of the machine is provided with a cup-shaped head 58 that fits over the shoulder of shaft 15 and the extended end of the bushing 59 surrounding said shaft in its bearing, and said head is provided with a peripheral set of gear teeth 60. An annular friction ring 61 is pinned or otherwise secured to the outer face of the head 58, the central opening of said ring being adapted to fit over the inner tubular portion of the sleeve. The pulley 43 before mentioned, is provided on its face adjacent this friction ring 61, with a smooth surface so as to frictionally engage said ring. A friction ring 62 is mounted on and rotatable with the sleeve 55 by means of a transaxial headed pin 63, the head whereof projects into a longitudinal groove 64 upon the outer periphery of said sleeve so as to permit its removal longitudinally therefrom. An expansion spring 65 is coiled around the sleeve 55 between its outer end and said friction ring 62 and is kept under tension by a cup-shaped cap 66 mounted upon the outer portion of the sleeve and inclosing said spring. This structure permits the pulley 16 and the smaller pulley 43 to rotate normally with the shaft 15, but 130

when the stop mechanism is operated by moving a reciprocable bolt 68 into the path of the transverse bolt 67, carried on the head of the sleeve, the rotation of the shaft 5 and its driven elements is instantly stopped while the pulleys 16 and 43 are stopped more gradually, due to the fact that the pulley 16 is frictionally secured to the shaft 5. The stop-mechanism is provided for the purpose of stopping the film-actuating shuttle instantly and at a predetermined position relative to the film to avoid spoiling quantities of the film and also to position the film positively relative to the aperture and other elements of the mechanism. This mechanism however forms the subject-matter of and has been more freely described in my copending application above mentioned and therefore needs no further detailed description herein.

In the above description and the drawings forming a part thereof, I have disclosed numerous specific devices for carrying out the objects of my invention which, of course, may be readily modified or refined for the purpose of adapting the mechanism to divers types of machines, all of which will be obvious to others skilled in the art of cinematography. I desire it understood therefore that all such modifications or refinements are contemplated within the scope of my invention as expressed in the appended claims, and I do not therein limit myself to any particular type of apparatus to which my invention is applicable.

What I claim as new is:—

1. In motion picture apparatus, an arbor for mounting a spool of film, an arbor for mounting a take-up spool for receiving the film from said first mentioned spool, a main drive shaft, a pulley frictionally mounted upon said shaft, mechanism for stopping the movement of said shaft, devices operatively connecting said pulley and first mentioned arbor, and means for disconnecting said devices.

2. In motion picture apparatus, an arbor for mounting a spool of film, an arbor for mounting a take-up spool for receiving the film from said first mentioned spool, a main drive shaft, a drive pulley frictionally mounted thereon, mechanism for stopping

the movement of said shaft, a belt and pulley connecting said first mentioned arbor and pulley, and means for disengaging said belt from said drive pulley.

3. In motion picture apparatus, a drive shaft having a drive gear connected therewith, an idle gear and pinion actuated by said drive gear, mechanism for stopping the movement of said drive gear, an arbor for a film spool supply, an arbor for a film take-up spool, means operatively connecting said take-up arbor and pinion, pulleys on said drive shaft and supply spool arbor, a belt connecting said last mentioned pulleys, devices for throwing said means out of operation, and film spools frictionally mounted upon said arbors.

4. In motion picture apparatus, a drive shaft having a drive gear connected therewith, an idle gear and pinion actuated by said drive gear, mechanism for stopping the movement of said drive gear, an arbor for a film supply spool, an arbor for a film take-up spool, means operatively connecting said take-up arbor and pinion, pulleys on said drive shaft and supply spool arbor, a belt connecting said last mentioned pulleys, devices engaging the aforesaid means for throwing said means out of operation, and film spools frictionally mounted on said arbors.

5. In motion picture apparatus, a drive shaft having a drive gear connected therewith, an idle gear and pinion actuated by said drive gear, mechanism for stopping the movement of said drive gear, an arbor for a film supply spool, an arbor for a film take-up spool, a belt operatively connecting said take-up arbor and pinion, pulleys on said drive shaft and supply spool arbor, a belt connecting said last mentioned pulleys, devices engaging said belt for throwing the same out of operative connection with said arbor and pulley, and film spools frictionally mounted on said arbors.

Signed at Chicago, county of Cook and State of Illinois, this 21st day of September, 1915.

ALBERT S. HOWELL.
